UNITED STATES PATENT OFFICE.

WILLIAM N. RUMELY, OF LA PORTE, INDIANA.

THRASHING-MACHINE SEPARATOR.

SPECIFICATION forming part of Letters Patent No. 284,675, dated September 11, 1883.

Application filed January 22, 1883. (No model.)

To all whom it may concern:

Be it known that I, WILLIAM N. RUMELY, a citizen of the United States, residing at La Porte, in the county of La Porte and State of Indiana, have invented a new and useful Improvement in Thrashing-Machine Separators, of which the following is a specification.

My invention relates to an attachment for that class of thrashing-machine separators known as "vibrator-separators" or "vibrators," and in which what are known as "shaking" ("tossing," "lifting," or "vibrating") rakes ("forks" or "fingers") are or can be used in connection with the "shaking" (or "vibrating") tables ("pans" or "chutes") of such separators; and

Figure 1 is a view of all the parts of my improvement. Fig. 2 is a side elevation of a vibrator thrashing-machine separator, showing my improvements attached. Fig. 3 shows a plan of one of the shaking-rakes of a vibrator-separator, and Fig. 4 shows in detail the construction of the bracket and the adjusting-bolt and nuts.

In the figures, C represents the cylinder-pulley; a a, a horizontal side piece of the frame of the separator; x x, an ordinary "shaking-pan" suspended by rods h h to the side piece, a a; m m, the side frame-piece of the pan x x; and P represents the pitman-rod, which imparts the vibrating motion to the shaking-pan.

B represents the rake cross-bar; f, the rake-fingers; v, bearings for the lower ends of the vibrating arms O. b is an angle-iron bracket; c, a bolt with a chamfered nut, n, and a jam-nut or lock-nut, n'. i is an eye in the bolt c; s, a helical spring; l, a loop of the latter; r, a loose wire loop, and p is a pin or key. The arrows ←→ indicate the direction of the oscillating motion of the parts to which they are adjacent.

The use of shaking-rakes similar to that shown in Fig. 3 is now common, and where arms are attached at v there are various means of imparting an oscillating motion to them, or of guiding their upper ends, as the construction may require. My invention has reference to guiding, adjusting, and cushioning the upper ends of the arms O of such rakes, and, as the result, to adjust the inclination of the rake teeth or fingers and to cushion the whole mech-

anism of the rake. I accomplish the above ends by the use of the helical steel springs s s, the adjusting-bolts c c, nuts n n' and n n', and the angle-iron brackets b b.

55

By reference to Figs. 1 and 2 it will be seen that the upper end of lever o can be adjusted so as to give less inclination to the fingers f by drawing the upper end toward the right hand. This is accomplished by loosening the nuts n and n' on the left of lever o and tightening the nuts n and n' on the right of the lever similarly, that a greater inclination may be given the fingers f by moving the lever and the nuts in the opposite direction. The springs s s hold 60 the lever o in the proper position while permitting that slight up-and-down motion of its upper end corresponding with and consequent upon the vibratory motion of the shaking-pan x x; and they at the same time cushion the 70 vibrations of the rake mechanism.

The details of the construction of my device are made evident from an inspection of Figs. 1 and 4.

In Fig. 4 an angle-iron bracket, b, is shown, 75 partly in section and bolted to the under side of the side frame-piece, a a, by means of bolts or screws n". Of course the brackets may be bolted in any position and to any object so long as the bolts c c retain a position approximately at right angles to the length of the lever o. The hole in the bracket b for the bolt c is made larger than the diameter of the bolt and is countersunk, and the nut n is chamfered to fit the countersink. The object of said construction is, that when the bolt c is under the pull of the spring s all the bearing and wear will come upon the chamfered surface of the nut n, and hence prevent abrasion of the threads of the bolt c. The nut n' is a jam-nut 80 or lock-nut, used to prevent the nut n from coming loose. One end of the spring s has a loop, l, which is placed around the top of the lever o, and the other is looped into the eye i of the bolt c. The lever o may have a shoulder upon which the loops l l of the springs s s may rest, or a piece of wire, r, may be looped around the lever o to answer instead of a shoulder. A pin or key, p, placed above the loops l l and through lever o prevents the 100 springs from becoming detached. The ends of the springs s s could, however, be fastened

to lever o otherwise, as by looping them through a hole or holes in the top of lever o .

What I claim as new, and desire to secure by Letters Patent, is—

- 5 The combination, with the rake-arm, of the helical spring s , the bolt c , provided with an eye and a chamfered nut, as shown and described, and the countersunk bracket b , as an

adjusting and cushioning device for one side, and a similar spring, bolt, and bracket as a similar device for the opposite side of the rake-arm.

WM. N. RUMELY.
